RECEPTACLE COVER

Rowland G. Curtis, Dover, Ohio, assignor to
 Reeves Steel and Manufacturing Company,
 Dover, Ohio, a corporation of Ohio

Application June 3, 1938, Serial No. 211,636

3 Claims. (Cl. 220—56)

The invention relates to receptacles provided with removable self-locking covers, particularly to the covers for garbage cans or similar receptacles where it is desirable to provide a self-locking lid which cannot be accidentally removed by the force of the wind or by dogs or other animals attempting to get at the contents of the receptacle.

More particularly the invention relates to the general type of covers having a latching handle mounted at one side thereof and adapted to lock the cover upon the receptacle until the handle is manipulated to unlock and remove the cover.

It is known that covers have been produced having various forms of latching handles but all such devices of which applicant has knowledge have been more or less complicated and expensive.

The object of the present improvement is to provide a simple, inexpensive and efficient latching handle which may be easily operated and which holds the cover in locked position, and does not require gravity or spring operated means to be associated therewith.

Another object is to provide a one-piece latching handle formed of sheet metal rigidly connected at one end to the depending flange of the cover, the other end having a latching portion formed thereon and extending through the cover for engagement under the usual rim bead of the receptacle.

These objects together with others which will be apparent from the drawing and following description, or which may be later referred to, may be attained by constructing the improved latching handle in the manner illustrated in the accompanying drawing in which:

Figure 1 is a side elevation of a receptacle provided with a cover having the improved latching handle thereon;

Fig. 2, a fragmentary top plan view of the cover and improved latching handle with parts broken away to show the manner in which the latching portion of the handle engages beneath the bead of the receptacle;

Fig. 3, a section taken as on the line 3—3, Fig. 2;

Fig. 4, a view similar to Fig. 3 showing the handle in unlocked position and the cover partly raised;

Fig. 5, a fragmentary vertical sectional view through a portion of the cover and receptacle diametrically opposite to the latching handle; and

Fig. 6, a detached perspective view of the latching handle.

Similar numerals refer to similar parts throughout the drawing.

A garbage can or similar receptacle of conventional form is indicated generally at 10, and as in general practice, the side wall of the receptacle 5 adjacent to its open upper end is provided with a laterally projecting means such as the outwardly extending bead 11, which serves the usual purpose of strengthening and reinforcing the rim of the receptacle and also acts as a means to be 10 engaged by the latching handle carried by the cover and comprising the present invention.

Both the receptacle and cover, as shown, may be of the usual circular form which is the common shape for such receptacles, although the 15 cross-sectional shape of both the receptacle and cover may be of any other suitable or desired form without departing from the invention.

The cover for the receptacle is indicated generally at 12, and may be of any usual and suitable 20 design and provided with the customary depending peripheral flange 13 adapted to overlie and enclose the bead 11 of the receptacle in usual and well-known manner.

The improved latching handle to which the invention pertains is indicated generally at 14, and is stamped from a single piece of sheet metal into a substantially U-shape as best shown in Figs. 2 and 6, one leg 15 having an angular outturned foot 16 adapted to be connected to the rim 13 25 of the cover by any suitable means such as a rivet 17 located through an opening 18 in the foot, or by spot welding or the like.

This handle may be curved transversely as indicated at 19 for the purpose of strengthening 35 the same and the other leg 20 is provided at its end with the flat, preferably narrower, latching portion 21 located through a slot 22 in the depending flange 13 of the cover and terminating in the angular end portion 23 adapted to normally contact with the exterior of the receptacle as shown in Figs. 2 and 3, and to contact with the interior of the flange 13 when the handle is operated to unlock the cover as shown in Fig. 4.

Preferably, at a point on the cover flange 13 40 diametrically opposite to the latching handle above described, some means such as the clip 24 may be provided to project inwardly for a sufficient distance to engage beneath the under side of the bead 11 of the receptacle and prevent 50 this side of the cover from being raised relative to the receptacle.

It is not necessary that the handle be formed of spring steel in order that it will properly operate, but ordinary sheet metal formed in the man- 55

ner illustrated and described, gives the handle sufficient rigidity to permit its use in removing and replacing the lid while at the same time it has sufficient flexibility so that it will operate 5 properly as a latching handle and may be pulled out to the position shown in Fig. 4 for removing the cover and at the same time when the handle is released it will resume the normal position as 10 shown in Figs. 2 and 3 with the latching portion 10 contacting the outside of the receptacle.

Assuming that the cover is placed upon the receptacle in the manner shown in Fig. 3, the handle will assume the position shown in said figure, the latching portion 21 thereof extending 15 through the flange 13 of the cover substantially into contact with the outside of the container and located directly beneath the bead 11 of the receptacle.

Any attempt to raise the cover relative to the 20 receptacle, without grasping and pulling outward upon the handle 14, will be opposed by the latching portion 21 of the handle engaging the under side of the bead 11 of the receptacle.

If, however, the handle 14 is pulled outward 25 to the position shown in Fig. 4, the latching portion 21 of the handle will be drawn out of the path of the bead 11 of the receptacle so that the cover may be raised relative to the receptacle as shown in said figure in order to remove the 30 cover from the receptacle.

With the construction illustrated and above described the cover is positively held upon the receptacle at all times excepting when the handle is manipulated to remove the cover.

35 The receptacle may be up-set, thrown or rolled into any position without the possibility of the latching handle becoming unlocked, as there is sufficient rigidity in the handle to hold the same in locked position.

40 I claim:

1. In combination with a receptacle having laterally projecting means at its open end, a

cover having a depending flange adapted to overlie and enclose said projecting means, and a substantially U-shaped horizontally disposed, flexible, resilient sheet metal handle rigidly connected at one end to the depending flange and having its other end extending through a slot in the flange and between the side wall of the receptacle and the rim flange of the cover and comprising a locking projection normally positioned beneath said laterally projecting means, 10 said last named end having a lateral projection thereon functioning as a stop to prevent said end from being removed from the slot.

2. In combination with a receptacle having laterally projecting means at its open end, a 15 cover having a depending flange adapted to overlie and enclose said projecting means, and a substantially U-shaped horizontally disposed, flexible, resilient sheet metal handle rigidly connected at one end to the depending flange and 20 having its other end reduced and extending through a vertical slot in the flange into position beneath said laterally projecting means and terminating in an angular end portion for engagement with the inside of the depending flange 25 when the handle is flexed.

3. In combination with a receptacle having laterally projecting means at its open end, a 30 cover having a depending flange adapted to overlie and enclose said projecting means, a substantially U-shaped, horizontally disposed, flexible, resilient sheet metal handle having one end outturned and rigidly connected to the depending flange and having its other end reduced and extending through a slot in the flange and terminating in an angular end portion forming a locking projection normally positioned beneath said laterally projecting means and arranged to contact the inside of the depending flange when the handle is flexed outwardly.

ROWLAND G. CURTIS.
